UNITED STATES PATENT OFFICE.

FREDERICK G. SARGENT, OF WESTFORD, MASSACHUSETTS.

DETECTOR.

1,013,223.

Specification of Letters Patent.

Patented Jan. 2, 1912.

Application filed January 28, 1910. Serial No. 540,512.

To all whom it may concern:

Be it known that I, FREDERICK G. SARGENT, a citizen of the United States, residing at Westford, in the county of Middlesex and 5 State of Massachusetts, have invented a new and useful Detector, of which the following is a specification.

This invention relates to a receiving station adapted for use with wireless apparatus, 10 as well as with ordinary telephone systems.

The principal objects of the invention are to provide improved means for receiving or detecting Hertzian waves of such construction that no coherer consisting of granular 15 material will have to be used; to provide a wire detector having a contactor engaging it in such a way that it will have a sliding motion on the wire; and to provide means whereby the battery ordinarily employed at 20 the receiving station can be dispensed with. These objects are accomplished by the employment of a detector consisting of a suspended vibratory wire contactor and a contact point adapted to engage the same.

25 The invention also involves several improvements in the details of construction as will appear hereinafter.

Reference is to be had to the accompanying drawings in which—

30 Figure 1 is a diagrammatic plan of a receiving station constructed in accordance with this invention. Fig. 2 is a diagram of a modified form of wiring. Fig. 3 is an elevation of a modified form of detector. Fig. 35 4 is an elevation of another modification of a detector coming within the scope of this invention, and Fig. 5 is an elevation of another modification.

As shown in Fig. 1 the receiving station 40 comprises an aerial 10 for receiving the waves provided with a tuning coil 11 having adjustable terminals whereby the resistance can be varied. This aerial is connected with a binding post 12. With this binding 45 post is connected an adjustable support 13 mounted on a bracket 14. Connected with this adjustable support is a resilient conductor 15 formed of iron or steel and preferably in the form of a flat wire, although 50 the cross section can be varied within wide limits. It is made of soft iron or steel so as to have a capability of keeping a slight amount of residual magnetism. No external magnetic field is used. The wire may have

more temper at one point than elsewhere if 55 desired. Although its own resiliency is ordinarily sufficient, I have shown coil springs 29 near its ends. The opposite end of this conductor is supported by a clamp 16 which is carried on the end of a flexible support 60 17 adapted to be adjusted by a screw 18 and mounted on a bracket 19. The brackets 14 and 19 are mounted on an insulating plate or slab 20. The detector wire 15 is shown in this figure as provided with an off-set 21 65 which during vibration causes a slight longitudinal motion of the adjacent parts of the wire. A detecting contact member 22 engages the wire either at the off-set as shown in Fig. 1 or in the straight longitudinally 70 vibrating part of the wire as indicated in Fig. 5. This contact member may be made of carbon, carborundum, zincite, steel, iron, silicon or other conducting material. It is mounted on a vibrating support 23 which 75 is fixed on an insulated bracket 24. The member 22 is adjustably mounted on the support by means of a screw 25 and nut and the support itself is capable of adjustment toward the wire 15 by a screw 26. The flexible 80 support 23 is shown as provided with a light spring 27 having an insulating head 28 thereon engaging the wire 15. This is for the purpose of holding the carbon point away 85 from the wire and returning it after coherence so as to decohere the parts, but obviously this can be accomplished by the arrangement of the resilient support 23 if desired without the spring 27.

The contacting point 22 is shown as provided with a conical or wedge shaped end adapted to engage the off-set portion 21 of the conductor 15. The surface of the point 22 preferably is substantially parallel with the adjacent surface of the conductor and 90 their relative motion is a sliding one as well as a lateral vibration. In view of the fact, that the screws 18 and 18 provide for the adjustment of the wire 15 longitudinally as well as for the stretching or tuning thereof, 95 it will be seen that the wire 15 can be moved so that the contact between the parts 21 and 22 can be made as light or heavy as may be necessary. In fact the conductor can be moved over so that the point 22 engages the 100 opposite side of the off-set at a fresh point. On this account the device is tuned in two 105 ways, one by adjustment of the wire 15

into and out of contact with the carbon point and the other by lengthening or shortening it so as to tune the same to the pulsations of the make and break of the primary circuit at the primary station. The resilient support 23 is electrically connected with the binding post 30 which is connected with the ground through a condenser 31. The binding posts 12 and 30 are connected 10 by a secondary circuit 32 which involves a potentiometer 33 and a receiving instrument 34 shown as a telephone receiver. The potentiometer can be wound with copper wire for induction or wound in the usual 15 way for resistance and induction, and is shown as having two adjustable terminals.

I have found in practice that this device is so sensitive that it can be successfully employed without a battery. When a battery 20 35 is employed, it is connected up as shown in Fig. 1 so that by turning the switch 37 the battery can be included or the receiver can be connected between the two binding posts preferably in series with a variable 25 condenser 36 as shown in Fig. 2 without the battery. By proper adjustment of the parts the condenser can be dispensed with. This device can be used with a telephone transmitter when connected up in the way in 30 which they are usually connected.

In the form of the invention shown in Fig. 3, the detector comprises a resilient iron or steel member 40. This is shown as provided with an adjusting screw 41 at one 35 end capable of being turned to draw the detector longitudinally and effect the contact thereof with the carbon point 42. In this case one end of the wire is connected by a fine steel coil spring 44 with a stationary 40 support 45. An adjusting screw 43 is provided which adjusts the spring. It will be seen that when the wire 40 is wound up on the screw 41 there will be a longitudinal motion of the whole wire 40 which will change 45 the point of contact thereof with the contact point 42 so that both kinds of adjustments are secured in this case as in the form shown in Fig. 2.

In the form shown in Fig. 4, one of these 50 adjustments is omitted, the conducting wire 50 being fixed to a stationary bracket 51 at one end and extending beyond the same. The wire 50 in this case is very short but it has an offset 52 shown of different shape 55 from that illustrated in Fig. 1 and is connected with the spring 53 which is adjustable by a screw 54 chiefly for affecting the resiliency of the construction.

In Fig. 5 the vibrating support 23 has a 60 spring 55. By first moving the support 23 so the contact point 22 comes very close to the wire, and then adjusting the screw, a very sensitive adjustment is secured.

In all the forms the contact point may be 65 normally in contact with the conducting

wire, or when the battery is not used the contact point may be just out of contact so that when the wire vibrates they will touch.

While I have shown and described certain preferred embodiments I am aware that many modifications can be made therein by any person skilled in the art without departing from the scope of the invention as expressed in the claims. Therefore I do not wish to be limited to all the details shown and described but

What I do claim is:—

1. A detector for the purpose described, comprising a conductor having an off-set therein and supported so as to vibrate when affected by Hertzian waves, means for connecting the conductor with a receiving aerial, and a vibratory contacting point adapted to engage the off-set portion thereof and connected with the ground. 85

2. A detector for the purpose described, comprising a metallic resilient conductor having a portion located at an angle to the general length of the conductor, a resiliently mounted contact point adapted to engage 90 the conductor near said inclined portion, and means for effecting a relative adjustment between the contact point and conductor longitudinally of the latter to vary the contact between them. 95

3. A detector for the purpose described, comprising a conductor of iron or steel, longitudinal adjusting means for supporting one end of the conductor, and longitudinal adjusting means for the opposite end of the conductor, whereby the longitudinal position of the conductor can be varied and whereby it can be tuned and a contact point in position to engage the conductor, with a variable pressure whereby the pressure of the contact may be varied by said adjustments. 100

4. A detector for the purpose described, comprising a conductor, means for supporting one end thereof, a resilient support at 110 right angles to the conductor near its opposite end to which said conductor is secured, means for transversely adjusting the tension of said resilient support and a contact point in position to engage the conductor. 115

5. A detector comprising a wire supported near its ends, independent means for longitudinally moving and adjusting both ends thereof and a contact point in position to engage the conductor with a contact variable by said adjustments. 120

6. A detector for the purpose described, comprising a longitudinally adjustable metallic conductor resiliently supported, and a contacting point adapted to engage said conductor and capable of vibrating transversely with respect to the direction of said adjustment, said conductor being free from the influence of external magnetic fields. 125

7. A detector for the purpose described, 130

comprising a conductor and a contact point adapted to engage the conductor, said conductor and contact point having a relative sliding motion when the conductor vibrates.

- 5 8. A detector for the purpose described comprising a transversely vibratable wire having a surface at an angle with the direction of its length, and a contact member having a surface substantially parallel with 10 said surface and in light contact therewith,

whereby when the wire vibrates there will be a sliding motion of one of said surfaces on the other.

In testimony whereof I have hereunto set my hand, in the presence of two subscribing 15 witnesses.
